UNITED STATES PATENT OFFICE.

CHARLES A. PHILLIPS, OF SAN FRANCISCO, CALIFORNIA.

CHIROPRACTIC TABLE.

Application filed January 23, 1923. Serial No. 614,361.

To all whom it may concern:

Be it known that I, CHARLES A. PHILLIPS, a citizen of the United States, residing at city and county of San Francisco and State of California, have invented certain new and useful Improvements in Chiropractic Tables, of which the following is a specification.

The present invention relates to improvements in chiropractic tables and the invention has among its objects to provide a table whereby the leg support is adapted for adjustment to and from the chest support; one wherein the edge of the chest support adjacent the head rest is capable of yielding movement to admit of the adjustment of the vertebrae at the base of the neck. Other objects of the invention are to provide a novel form of pivotal construction for the leg support and chest support and to incorporate in connection therewith variable tension means and locking mechanism. A further object is to provide a head rest adjustable as to height and variable as to distance from one edge of the chest support. Other objects will appear from a reading of the detailed description of the preferred embodiment hereinafter set forth.

With the above mentioned and other objects in view, the invention consists in the novel construction and combination of parts hereinafter described, illustrated in the accompanying drawings, and set forth in the claims hereto appended, it being understood that various changes in the form, proportion, size and minor details of construction within the scope of the claims may be resorted to without departing from the spirit or sacrificing any of the advantages of the invention.

Figure 1 is a longitudinal sectional view taken on the line 1—1 of Fig. 2 illustrating more particularly the pivotal mounting of the chest and leg support.

Fig. 2 is a longitudinal transverse sectional view taken on line 2—2 of Fig. 1 illustrating particularly the means for locking the chest and leg support from pivotal movement.

Figure 3 is a view in side elevation of the preferred embodiment of my invention.

Fig. 4 is a transverse sectional view taken on line 4—4 of Figure 1.

Figure 5 is a transverse sectional view taken on the line 5—5 of Fig. 1 through a pivotal point of the leg support.

In the drawings, 1 indicates the elongated rectangular base having a raised portion 2 at one end and within said raised portion there is mounted the head rest standard 3. The guide 3 is adapted for vertical adjustment, the head rest standard 4 curved at its upper end at 5, and which pivotally mounts as at 6, the head rest 7 preferably carrying cushioned or yieldable upper surface 8. The member 4 is retained in its adjusted position by any suitable means such as the adjustable jam screw 9, the outer end of which is bent as at 10 and weighted as at 11.

At the opposite end the base 1 is provided with the rectangular raised portion 12, the side members 13 of which are peaked as at 14. At their apex a fulcrum rod 15 passes therethrough and extends through the side members 19 of the rectangular frame 20 of the adjustable leg support. This latter member consists of a bottom board or portion 22 secured to the frame 20 and which on its upper surface the board mounts a spring cushion 23. A coiled spring 24 resists the downward pivotal movement of the front edge A of the leg support and said spring is united at its lower end preferably to the rear wall of the member 12 as at 25. To lock the leg support from pivotal movement and at the desired angle, I provide a pivoted link 26 depending from the member 22 and its lower apertured end passes through the bifurcated guide 27. A lock pin 28 operated by a bell crank lever 29 is adapted for reception within the apertures in the link 26. The bell crank lever is mounted on the plate 30 and is normally held in raised position by a spring 31. The free end of the lever which is weighted as at 32, extends through the wall of the member 12 and through a notched plate 33, the lower notch 34 of which is adapted to receive the free end of the bell crank and hold the pin 28 in its retracted position.

To enable the adjustment of the leg sup-

port and its mounting 12 longitudinally of the base 1, the base side walls on their respective inner faces are grooved as at 35 and within the same are received guide members 36 secured to the side walls 13 of the member 12. The finishing plate 37 extending forwardly from the member 12, is adapted to telescope beneath a corresponding finishing plate 38 rigidly secured to the side walls of the base 1 in advance of the normal position of the adjustable leg support. A chest support is pivotally mounted to the uppermost extension 39 of the raised portion 2 of the base and the same is constructed in the following manner. A substantially triangular frame consisting of the horizontal leg portion 40, vertical leg portion 41 and inclined leg portion 42 is fulcrumed at one corner to pivot on the transverse rod 43 mounted in the side walls of the member 39. This construction is mounted with the frame overhanging facing the forward edge of the leg support. The respective members 40, 41 and 42 forming the ends of the frame, are connected by the transverse connecting members 44, 45 and 46. A cushion bottom board 47 rests on the upper edge of the horizontal legs 40 of the triangular frame and at one end is hinged as at 48 to the edge of the transverse member 45, the member 47 falling short of overlying the fulcrum member 43. In continuing the member 47 over and beyond the fulcrum member 43, I employ the parallel strips 49, the adjacent edges of which are downwardly inclined as at 50 away from each other, the upper meeting edges of the strips are hinged together as at 51 to permit the downward flexible movement of the strips over the downwardly beveled edge 52 of the member 45. This construction lends flexibility to that edge of the chest support facing the inner edge of the head rest. Over the upper surface of the edge 52 and board 47 is positioned a cushion 53 similar in construction to the cushions 8 and 23, respectively, used in connection with the head rest and legs support. The springs 54 of the cushion 53 assist in normally maintaining the surface of the strips 50 in a plane parallel with the surface of the board 47.

To control the pivotal movement of the triangular frame in one direction, I provide a transverse stop 55 connecting the side members at the base 1 and at a point below the fulcrum 43. With this stop is adapted to contact the lower edge of the members 41 on the swinging of the long leg of the frame to a horizontal position. To lock the chest support in this position and to prevent the same from pivoting on the fulcrum 43, I employ the pivoted frame 56 fulcrumed as at 57 between the walls of the base 1 and adapted for operation by the weighted lever

58 extending exteriorly of the base 1. The movement of the frame 56 to contact with the member 46 locks the triangular frame of the chest support against the angle rod 55 and precludes pivotal movement thereof until the frame 56 is swung free of the member 46. To oppose the pivotal movement of the chest support, I provide the coil spring 58' connected through the adjustable eye bolt 59 with the member 46. The other end of the spring 58' is connected through an adjustable eye bolt 60 with a lever 61 fulcrumed as at 62 within the base 1 and the free end of the lever extends outwardly through the sides of the base 1 and is provided with an operating handle 63. A notched and slotted plate 64 through which the lever 61 extends provides a means for holding the lever in different angular positions to regulate tension on the spring 58.

By this construction it will be observed that all controls for the different supports extend from the base at one side, also that the legs support is adapted for adjustment to and from the chest support, and that the head rest due to the bent end of the member 4 is adapted for movement to and from the forward edge of the chest support by axially rotating the support 4 of the head rest. It will also be understood that the legs support is adapted for pivotal movement opposed by the tension of spring 24 and is also capable of being locked in a horizontal or angular position. It is also possible to lock the chest support from pivotal movement and to vary the tension of the spring opposing the pivotal movement when such movement is permitted. It will be understood that by making the forward edge of the chest support of such construction as will permit the same to bend downwardly, that the work of the operator in performing certain adjustments is materially expedited.

Having thus described my invention, what I claim as new and desire to secure by Letters Patent, is:

1. A chiropractic table including a base, a legs support at one end thereof, a head rest at the other end thereof, a chest support positioned between the head rest and legs support, the latter including a frame pivotally mounted to swing on a horizontal axis, the frame including a cushioned bottom board provided at its edge facing the head rest with a plurality of transversely disposed sections, and means for hingedly connecting the sections to swing downwardly on a horizontal axis.

2. A chiropractic table including a base, a legs support at one end thereof, a head rest at the other end thereof, a chest support positioned between the head rest and legs support, the latter including a frame

pivottally mounted to swing on a horizontal axis, the frame including a cushioned bottom board provided at its edge facing the head rest with a plurality of transversely disposed sections, means for hingedly connecting the sections to swing downwardly on a horizontal axis, and yielding means for

normally maintaining the hinged sections in substantially the same plane with the bottom board.

10

In testimony whereof I have signed my name to this specification.

CHARLES A. PHILLIPS.
